Patented May 1, 1917.

UNITED STATES PATENT OFFICE.

GEORGE L. KOLLOCK AND ROBERT P. MARTIN, OF SEATTLE, WASHINGTON, ASSIGNEES
TO UNIVERSAL HAMMER COMPANY, OF SEATTLE, WASHINGTON, A CORPORATION
OF WASHINGTON.

HAMMER.

1,224,471.

Specification of Letters Patent.

Patented May 1, 1917.

Application filed January 31, 1916. Serial No. 75,322.

To all whom it may concern:

Be it known that we, GEORGE L. KOLLOCK and ROBERT P. MARTIN, citizens of the United States, residing at Seattle, in the 5 county of King and State of Washington, have invented certain new and useful Improvements in Hammers, of which the following is a specification.

This invention relates to electrically controlled spring hammers of the class shown 10 and described in our patent application, Serial No. 49,243, filed Sept. 7, 1915.

The object of the present invention is to provide a more efficient and inexpensively 15 constructed tool of this nature, and the several improvements have in view these general results.

The invention consists in improvements in 20 the entire machine and its various parts, and include, mainly, the frame, a spring-actuated hammer member provided with a cam element, a power driven rotary member co-operating with said cam element to retract the hammer member, and electrical means 25 to operate and regulate the action of said rotary member.

The invention further consists in the novel 30 construction, adaptation and combination of parts, as will be hereinafter described and claimed.

In the accompanying drawings, Figure 1 is a longitudinal sectional view partly in elevation, of an embodiment of our improved hammer. Fig. 2 is a similar view of portions 35 of the hammer member and the controller therefor shown in positions at right angles to those in which they are represented in Fig. 1. Fig. 3 is a transverse longitudinal section illustrating a modified form 40 of construction for the cam element of the hammer member. Fig. 4 is a sectional view through 4—4 of Fig. 3. Fig. 5 is a fragmentary elevational view of a controller adapted for use with devices shown in Figs. 3 and 4. Fig. 6 is a diagrammatic view of the electric 45 appliances employed in the invention. Fig. 7 is a longitudinal fragmentary sectional view of the casing with the hammer shank shown in elevation to illustrate the latter 50 in modified form.

The casing of the hammer is formed of axially aligned cylindrical and tapering portions 11 and 12. This casing is provided in the part 11 with a chamber 13 terminating 55 at a shoulder 14, and connects with a bore 15

which extends through the tapered part 12. Operable within said bore is the shank 16 of a striking or die member having at one end a die element 17 and at its other end a cam element 18. The shank 16 may, however, be divided, as at 19, to form two co-operating members whereof the one carrying the die element is impinged by the other which is thereby actuated to impart blows against the work.

The referred to cam element in its preferred form, Figs. 1 and 2, consists of a tubular head 20 formed in its inner periphery with two symmetrically arranged helical trackways 21 and 21¹ each of which extend about a half of the circumference and terminate at axially disposed ridges 22 at diametrically opposite sides.

The head 20 is of less diameter than said chamber to afford an annular space 23 for a spring 24 which is interposed between a partition 25 provided in the chamber and a peripheral flange 26 provided on said head. Spline elements 27 are formed or provided on the head flange 26 and operable in grooves 28 in the casing wall to prevent the hammer member rotating during its reciprocatory movements. Co-operating with said cam element and fitting within the same, is a cylindrical body 29 carrying at opposite sides 85 studs 30 upon which are mounted rollers 31 adapted, when revolvably moved, to alternately engage the trackways 21 and 22¹ and effect an axial movement of the hammer member in opposition to the spring 24, until the rollers pass beyond the respective ridges when the spring asserts itself to operate the hammer member.

The body 29 is rigidly secured to a shaft 32 extending through the partition 25 and at the other side of the same has formed thereon or secured thereto an internal toothed gear 33 which is driven by an intermediate gear 34 from a pinion 35 provided in the armature shaft 36 of an electric 100 motor 37. This motor is located in a compartment intermediate the partition 25 and a removable closure 38 provided for the upper end of the casing part 11.

The handle 39 for the hammer is made 105 hollow for the reception of a resistance coil 40 which may be included or otherwise, in the motor circuit 41 through the agency of a suitable switch which is designated by 42.

43 represents a spring-opening switch 110

whereby an electric current may be supplied to energize said motor when the switch is closed by the operator manipulating finger 43¹ to move the switch into couple with the 5 contact 44.

A spring washer 45 or an equivalent, is provided on the shoulder 14 to afford a cushion to receive the blow of the striking member when not delivered against the work. 10 46 represent roller thrust bearings to reduce the friction due to the end thrusts derived from the lifting and striking power agents.

The modification shown in Figs. 3 and 4 15 illustrates a manner or means for providing a cam element 20¹ with helical trackways 21² and 21³ which extend entirely around the inner periphery of the cam and disposed one above the other. With such a construction of cam, the coöperating body 29¹ has the rollers 31¹ therefor arranged at a spaced distance apart axially of the body. 20

The operation of the invention is as follows:

25 With the resistance coil 40 in or out of circuit, according to the required power, the motor 37 upon being energized, imparts rotary motion through the gear train 35, 34 and 33 to the body 29, revolving the rollers 31.

These rollers tracking against the ways 21 and 21¹ of the cam 20, cause the latter

and the striking member 15 to be moved upwardly and compress the opposing spring 24.

When the rollers 31 have been revolved 35 beyond the ends of the respective ways, the striking element becomes unsupported thereby; whereupon the spring asserts its power to drive the striking member downwardly to perform its duty. The body 29 continuing 40 to rotate again elevates the striking member which is again influenced by the spring to afford reciprocatory movements to the striking member. 45

What we claim, is—

Apparatus of the class described, comprising a casing, a striking member arranged for reciprocatory axial movements, a compression spring engaging said striking member, a hollow cam provided on said striking member, means extending axially into and engaging said cam, an electric motor, and operative connections between the latter and said means for actuating the same to effect an endwise movement to said striking member. 50

Signed at Seattle, Washington, this 5th day of January 1916.

GEORGE L. KOLLOCK.
ROBERT P. MARTIN.
